SHIRT CUFF

Robert V. Kay, 1246 S. 51st Court, Cicero, Ill.

Filed Oct. 12, 1964, Ser. No. 82,132

Term of patent 14 years

(Cl. D3—8)

Fig. 1

Fig. 2.

Fig. 3.

I claim:

The ornamental design for a shirt cuff, substantially as shown and described.
